COMBINED CLOCK FACE AND CHIME SIGNAL HOUSING

John G. Jolly, Cincinnati, Ohio, assignor to NuTone, Inc.,
Cincinnati, Ohio, a corporation of New York

Application March 26, 1958, Serial No. 50,181

Term of patent 14 years

(Cl. D42—7)

Figure 1 is a front elevational view of a combined clock face and chime signal housing showing my new design.

Figure 2 is a side elevational view thereof.

Figure 3 is a top plan view thereof.

Figure 4 is a cross sectional view taken on the line 4—4 of Figure 1.

The side, not shown, is substantially identical to the side shown in Figure 2. The bottom, not shown, is substantially identical to the top shown in Figure 3.

I claim:

The ornamental design for a combined clock face and chime signal housing, substantially as shown and described.
